(57) **CLAIM**

The ornamental design for a gun video game controller with scope, as shown and described.

DESCRIPTION

FIG. 1 is a perspective view of a gun video game controller with scope in accordance with our design;

FIG. 2 is a left side view of the gun video game controller with scope of FIG. 1;

FIG. 3 is a top view of the gun video game controller with scope of FIG. 1;

FIG. 4 is a right side view of the gun video game controller with scope of FIG. 1;

FIG. 5 is a bottom view of the gun video game controller with scope of FIG. 1;

FIG. 6 is a front view of the gun video game controller with scope of FIG. 1;

FIG. 7 is a rear view of the gun video game controller with scope of FIG. 1;

FIG. 8 is a rear perspective view of the gun video game controller with scope of FIG. 1;

FIG. 9 is a perspective view of an alternate embodiment of a gun video game controller with scope in accordance with our new design;

FIG. 10 is a left side view of the gun video game controller with scope of FIG. 9;

FIG. 11 is a top view of the gun video game controller with scope of FIG. 9;

FIG. 12 is a right side view of the gun video game controller with scope of FIG. 9;

FIG. 13 is a bottom view of the gun video game controller with scope of FIG. 9;

FIG. 14 is a front view of the gun video game controller with scope of FIG. 9; and,

FIG. 15 is a rear view of the gun video game controller with scope of FIG. 9.
